UNITED STATES PATENT OFFICE.

JOSEPH LEHNE, OF CHARLOTTENBURG, GERMANY, ASSIGNOR TO INTERNATIONALE ROTATIONS-MASCHINEN-GESELLSCHAFT M. B. H., OF BERLIN, GERMANY.

FLUID TRANSMISSION.

1,042,696.

Specification of Letters Patent. Patented Oct. 29, 1912.

Application filed May 4, 1910. Serial No. 559,353.

To all whom it may concern:

Be it known that I, JOSEPH LEHNE, engineer, a subject of the Grand Duke of Hesse, residing at Charlottenburg, Germany, have 5 invented certain new and useful Improvements in Fluid Transmission; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 My present invention relates to rotary machines, and more particularly to that class of such machines used for the transmission of liquid or as power devices operated by a liquid, or both, as will hereinafter 20 be more particularly described and claimed.

The main feature of this invention relates to that type of rotary machines in which any number of slides acting as pistons are moved in radial slots or grooves in a rotor 25 or drum that rotates in a casing forming working spaces between the end surfaces or the circumferential surface of said drum and the end surfaces or internal circumferential surface of the casing. Such machines 30 are of two general types, the axial type, wherein the slides move in their slots in a direction parallel to the axis of the drum, and the radial type in which the slides move in their slots radially to the axis of the 35 drum.

The working spaces have a varying width, as is well known; the size of the active working space, and, in the case of a pump, its capacity, will depend, under otherwise 40 identical conditions, on the differences in the width at the various points of said spaces, and not on their total size.

In the present invention, a controlling of the capacity of the rotary machine is obtained by controlling the size of the active working spaces. For this purpose the width of said working spaces is made variable. These working spaces may have a width variable to a maximum effective width beyond 45 which the increase in width is ineffective. This is attained by adjusting the stationary abutment or abutments that cooperates or that co-operate with the piston

slides, and in conjunction therewith in the axial type of rotary machine illustrated, also 55 by displacing the drum in which the slides are mounted, thereby varying the width of the working spaces swept by the slides, as will more fully appear hereinafter.

By a suitable combination of two working spaces a perfect compensation of pressure may be obtained as well as a delivery in either direction without requiring the reversal of the direction of rotation.

In the drawings in which like parts are 65 similarly designated, I have chosen to show one form of apparatus embodying my invention as applied to a fluid transmission, specifically, the primary part or pump of a hydraulic change or reversing gear for 70 power driven vehicles or the like, in combination with a motor of known type serving as a secondary motor that furnishes the direct or driving power for the vehicle.

Figure 1 is a vertical, longitudinal section of one form of rotary machine embodying my invention, the section of the motor M being taken on the line I—K Fig. 3. Fig. 2 is a section taken on line A—B of Fig. 1, the rotor or drum being rotated 45°. Fig. 80 3 is a vertical, transverse section of the secondary rotary motor on the line C—D Fig. 1. Figs. 4, 5 and 6 are developed diagrams illustrating the operation of the rotary machine or pump. Figs. 7 and 8 are, 85 respectively, elevation and plan showing a modified form of the lever mechanism for effecting the movement of the rotor or drum. Figs. 9 and 10 are developed diagrams showing two modifications of the rotary machine. 90 Fig. 11 is a perspective view partly in section, showing the interior of the lining at one end and the adjustable abutment. Fig. 12 is a perspective view of the radially grooved or slotted rotor.

95 The rotor or drum 1 of the rotary machine acting as a pump P, Figs. 1, 2, 4, 5 and 6, is provided with a plurality of radial grooves, in this particular instance with four, in each one of which is fitted a piston 100 slide 2 (a, b, c, d).

The rotor or drum is mounted in a cylindrical casing comprising, as shown in this particular instance, an outer shell a an inner shell b and a two-part lining c, c'. The 105 space between the outer shell a and inner

shell *b* is divided into two portions by webs, herein indicated as vertical webs *e*, Fig. 2, dividing the space between two shells into two circulating chambers, the suction and delivery chambers 9 and 9^a hereinafter referred to. The two parts of the lining are held distanced from one another by means of a ring *d* of lesser thickness than the lining and which is flush with the outer surface thereof. That portion of the space between the adjacent ends of the parts *c* and *c'* of the lining and not occupied by the spacing ring *d* forms a cam groove 6 in which rollers 5 on the slides 2 travel, whereby said slides are reciprocated.

10 The making of the lining in two parts permits the accurate shaping of the adjacent ends and facilitates the formation of the groove. This particular feature may be varied to suit the conditions of manufacture; the lining may be omitted altogether and the groove formed in the inner shell *b* or otherwise, the essential feature being the presence of a cam or cams to impart proper reciprocation to the slides in the radial slots of the rotor during the rotation of the latter.

15 Into the ends 3 and 3' of the casing that are opposite the ends of the rotor or drum 1, are arranged the stationary, but axially adjustable abutments 4 and 4' with which the slides coöperate to effect the movement of the liquid.

20 The slides 2 are guided in such a manner by their rollers 5 in the cam groove formed between the sections *c* and *c'* of the lining, that they will, in their one extreme position, be in contact with one end 3, and in their other extreme position be in contact at their opposite ends with the other end 3'.

25 The rotor or drum 1 is provided with a spindle 23 rigidly connected thereto and suitably driven. This spindle is supported in sleeve bearings 24 and 24' which are fitted between collars 36 and 36' on the spindle. On the bearing 24 is fitted a ring 25 engaged by a lever 26 connected by a link 27 to a lever 28 designed to be operated by hand. A cam 29 fitted to lever 28 limits the stroke of the link 27 by acting as a stop 30 at the terminal positions of said link.

35 On the sleeve bearings 24 and 24' are guided sleeves 31 and 31' respectively, under the action of springs 30 and 30' in such a manner that a certain relative movement 40 between the two sleeves 24 and 31, and 24' and 31' is possible. The abutment 4 is connected to the sleeve 31 and the abutment 4' to the sleeve 31'. The abutments 4 and 4' are 180° apart and extend over about 90°, as indicated in Figs. 1, 4, 5 and 6.

45 By operating the hand lever 28 preferably in relation to an arc, as shown in Fig. 7, the rotor or drum 1 can be shifted axially from the position shown in Fig. 1, where said drum is in contact with the end 3', to the

other extreme position in contact with the end 3, and vice versa, as well as to any intermediate position.

50 In front of one or the other abutment, 4, 4', or both of them (seen in the direction of the arrow indicating the direction of movement of the rotor or drum, Fig. 4), is formed a pressure space, 7 or 7' or both 7 and 7', depending upon the position of the rotor in the casing. These pressure spaces communicate with delivery ports 12 and 12', and behind each abutment there is a suction space 8 or 8' or both, communicating with admission ports 13 and 13'. In other words, each abutment is between an admission and delivery port formed by an opening through the lining and inner shell Figs. 1, 2 and 11. When the rotor or drum 1 is in either of its extreme positions Figs. 4 and 6, either the pressure spaces 7 and 8 or 7' and 8' are reduced to zero and only one end of the rotor is effective. The delivery ports discharge therefore into the delivery chamber 9 Fig. 4 or 9^a Fig. 6, while the suction ports receive fluid from the suction chamber 9^a Fig. 4, or 9, Fig. 6.

55 The rotor or drum 1 is provided with through passages 11 (*a*, *b*, *c*, *d*) one between each two neighboring piston blades so that the piston blades 2 and passages 11 alternate with one another, Figs. 2 and 12. These passages 11 through the rotor or drum 1 connect the delivery and admission spaces 7' and 8, and 7 and 8' at the two ends of the casing when the position of the rotor is such as to permit the presence of the spaces at both ends of the rotor. One of their objects is to equalize the hydraulic pressure at both ends of the rotor.

60 The pressure spaces 7 and 8' for example in Fig. 5 not only communicate with each other inside the casing through the passage 11^a but also outside the casing through the discharge port 12 at one end, and the admission port 13' on the other end, both of said ports communicating with the chamber 9 and extension 10 of chamber 9. This chamber 9 then acts as a by-pass in conjunction with 11^a. In like manner the pressure spaces 7' and 8 not only communicate with each other inside the casing through the passage 11^a, Fig. 5, but also outside the casing through the discharge port 12' at one end, and the inlet port 13 at the other end of the casing connected by chamber 9^a and its extension 10^a. Chamber 9^a also acts as a by-pass between these ports with 11^a. Thus it will be seen as each pair of adjacent piston blades 2 take up their positions, during the rotation of the rotor or drum 1, immediately behind or in front of the stationary abutments 4, 4', they will in the position shown in Fig. 5, connect the inlet and discharge ports through chambers 9 and 9^a now acting as by-passes, and consequently the rotary 65

machine in this particular position is ineffective or runs idle. The movement of the liquid at this time will be as follows, admission at port 13 moved by blades 2 through 5 delivery space 7 to discharge port 12, chamber 9 to inlet port 13' and admission space 8' at the other end of the rotor thence back through port 12', chamber 9^a, port 13, back to 8. The movement of the rotor 1 toward 10 the abutment 4' causes a throttling of the ports 7' and 8', consequently the quantity of liquid partaking in the idle circulation, or passing through the chambers 9 and 9^a acting as by-passes will decrease in accordance 15 with the size of the working spaces until these two ports are completely closed, as indicated in the position Fig. 4, wherein the abutment 4' has been forced against the stress of its spring 30' flush with the end of 20 the casing or cylinder which corresponds to the position shown in Fig. 1. In this position the admission and discharge ports at the right hand end of the cylinder Fig. 1, (lower portion of Fig. 4) are completely 25 closed by the rotor 1, and the abutment 4 projects into the cylinder or casing to its full extent, the same as in Fig. 5. The liquid is admitted or aspirated at 8 through admission port 13 on one side of abutment 30 4 and is discharged by the blades 2 through the port 12 on the other side of the abutment 4, the chambers 9 and 9^a will now act purely as admission and discharge chambers, while the passage 11 will still be effective for 35 equalizing the pressure on both ends of the rotor. The volume of liquid moved will correspond to the extent of the projection of abutment 4 from the end wall of the casing, and the movement will be from 10^a to 10, 40 Fig. 4.

Fig. 6 is just the opposite of Fig. 4, here the other end of the pump P works, and the same quantity of liquid as in Fig. 4 is moved from 10 to 10^a, reversed in direction.

45 Between the positions shown in Figs. 4 and 5 and 6 and 5 there are any number of intermediate positions. At all intermediate positions between those shown in Figs. 4 and 5 the active working space or chamber is 50 greater on the upper than on the lower side, because the abutment 4' advances from the face of the end of the casing, urged by its spring to follow up the shifting of the rotor, while the abutment 4 remains stationary.

55 At all these intermediate positions there is a flow, the same as in the position according to Fig. 5, from the upper space to the lower space through passage 9, but only a part of the liquid conveyed from the upper working 60 space can be received by the lower, smaller space, while the surplus is forced off through socket piece 10 and represents the delivery proper of the pump. In the same manner the quantity of liquid flowing from the 65 lower working space to the upper working

space through passage 9^a will not be sufficient to fill the upper space and the still required quantity is aspirated through socket piece 10^a. The effect is similar at the intermediate positions between Fig. 5 and Fig. 6, 70 only here the lower space holds a larger quantity of liquid, while the upper space serves as circulating space. Here furthermore, socket piece or union 10 is the suction one, and 10^a the delivery one, in other words, 75 the direction of the delivery is reversed.

From what has been described above it is evident that by means of my improved engine any quantity of liquid varying from zero to a maximum, within the limits of the 80 machine, may be conveyed in either the one or the other direction. The arrangement could also be made for a conveyance in one direction only and with a working space arranged on one side only. In such instance 85 the only condition to be observed would be, that the drum remains always in close contact with the abutment. However, the double sided arrangement affords the possibility of entirely relieving the pressure in 90 an axial direction, so that there will be no axial thrust of the rotor. This relief is obtained in the present instance by the drum being provided between each two slides with a passage 11 (a, b, c, d) through which the 95 corresponding axially opposite sections of the working space at each end are made to communicate, so that the same total pressure must exist on either side. For obtaining a compensation of pressure also in the terminal positions Figs. 4 and 6, the provision may be made, that at such positions the abutment still projects a little beyond the surface 100 of the casing, so that there remains a certain amount of play between the drum and the 105 casing. It is true, that this will mean a small loss of efficiency corresponding to the contents of the active working space remaining at this side. The passages 11 in the drum may also serve as passages for conducting the liquid from the pressure space 110 on the one side to the suction space on the other side, so that the chambers 9 and 9^a in the casing may be dispensed with, that is, they need not connect ports. The passages 115 11^a and 11^c will act in such a manner in Fig. 5. At the further travel of the drum in the direction of the arrow the passages remain fully open until their right hand edges meet the left hand edges of the abutments 4' and 4 respectively. From this moment the free sectional area of both passages will decrease 120 gradually until completely closed by the abutments. In the meantime the slides 2^a and 2^c will have been moved under action 125 of the curved groove 6 a distance upward and downward respectively, and a part of the liquid can flow from space 7 through the gap between the slide 2^c and the end of the casing and also through the port 12 leading 130

into space 7 around the outer edge of the slide as it traverses the port, and farther through the passage 11^b into the suction space 8'. In the same manner a part of the liquid can flow from space 7' through the gap between slide 2^a and the other end of the casing and around the edge of the slide as it traverses the port 12' and further through the passage 11^d into the suction space 8.

10 It will be noted that the admission and delivery spaces 7, 8, and 7', 8' in Figs. 4 and 6 have a portion of ineffective width, being that width included between the abutments and the ends of the rotor. It will thus be 15 seen that the capacity or efficiency of the pump for any one adjustment is dependent on the difference between the projections of the abutments into the working chamber.

The secondary motor M has, in the arrangement of a change or reversing gear illustrated in Figs. 1 and 3, the known form of a rotary machine, the piston drum 14 of which has a number of concentric grooves 15, say two, cut in each of its end surfaces, 20 which grooves are closed at one point by fixed abutments 16, whereas the radially movable slides 17, which ordinarily also close the grooves 15, are adapted to pass the abutments 16 by means of recesses or notches 25 18 provided in them. The controlling of the slides 17 is obtained by guiding their ends between equidistant curves 19, 19'. In front and behind the abutment 16 an opening 20 or 20^a respectively, in wall 21 leads 30 into every groove 15 in the end of the motor drum 14 toward the pump. The passages 20 communicate with passages 9, passages 20^a with passage 9^a. The communication between the grooves 15 on the 35 other side of the drum with the same passages 9, 9^a is obtained by means of axially arranged passages 22 passing through the drum between each two slides 17. The result is, that according to the direction of delivery of the pump P the motor M will 40 revolve in one or the other direction. At the same time the speed of the motor will vary with the volume of the delivery of the pump. By the use of this mechanism on a motor 45 driven vehicle it will thus be possible to drive forward or backward at any speed varying from zero to the given maximum by simply adjusting the drum 1 of the pump and its abutments 4 and 4' respectively.

50 55 The position shown in Fig. 1, corresponds to the position shown in diagram Fig. 4, in other words, the drum and the abutments are in their extreme position on the right (lowermost position Fig. 4) the abutment 4 is moved out fully, abutment 4' is moved back fully, spring 30' is compressed, spring 50 slack.

When the lever mechanism 26, 27, 28 is turned to the left, it will move the spindle 60 23 with the drum 1 to the left, the abut-

ment 4' will follow the drum under action of spring 30 until sleeve 31' strikes against stop 32', while the abutment 4 remains stationary until drum 1 comes into contact with it. The sleeve 31' meets stop 32' simultaneously with drum 1 meeting abutment 4, abutment 4' will now remain stationary, while abutment 4 together with sleeve 31 is carried along by the drum, the spring 30 being compressed thereby, until all parts 70 have reached their respective extreme position on the left.

In Figs. 7 and 8 the adjusting lever mechanism is shown in a somewhat different arrangement. Here, furthermore, safety valves 33, 33' are provided, through which the liquid may pass from the compression to the suction space when a given maximum pressure is exceeded. For the purpose of avoiding that the abutments 4, 4' are moved 80 outward against the smaller pressure of the springs 30, 30' by the greater pressure inside the pump, the space behind each abutment communicates with the respective delivery passage adjacent thereto, i. e., with 9 90 or 9^a when they carry pressure fluid.

In the constructional form according to diagram Fig. 9, the arrangement is such that the two abutments 4, 4' will be in close contact with the drum 1 in every position. The slides 2 are accordingly so dimensioned that their length corresponds to only the length of the drum. The abutments need no longer fill up a whole quadrant, as in the arrangement shown in Figs. 1 and 6, where such 100 was necessary so that the slide passing an abutment might remain in close contact with the same during a sufficient length of travel. Lastly the constructional form according to diagram Fig. 10 represents a reversal of the 105 hereinbefore described arrangements, in so far that the abutments 4, 4' are arranged on the inside, rigidly connected with a disk 34, while the drum and each slide are separated into two members connected with each other 110 in a rigid manner by suitable means. The slides 2 rotating with the drum are guided with their end surfaces on outwardly arranged equi-distant curved surfaces 35, 35'. The drum 1 is axially adjustable, the same 115 as in the other constructional forms, so that the working spaces lying between its two members and the stationary parts 3, 3' of the casing can be adjusted to any desired width.

Instead of combining the two working 120 spaces in one machine, as shown in the drawings, a suitable communication between the working spaces of two separate single acting machines may be employed for the same purpose. These two machines would then 125 be preferably arranged on the same spindle, so that they would relieve each other; they might, however, also have separate spindles and even run at different speeds.

It will be noted that the right and left 130

hand ends of the pump P act as separate machine units, there being a casing common to both of them.

I claim—

1. In a rotary machine, the combination of a casing, a rotary drum having radial grooves, slides arranged in said grooves, means for reciprocating said slides, a non-rotatable abutment in said casing and projecting into the working space between the casing wall and drum, said abutment and drum being adjustable to vary the effective size of the working space and thereby the quantity of fluid delivered by the machine. 10
2. In a rotary machine, the combination of a casing, a rotor having radial grooves, slides axially movable in said grooves, means for reciprocating said slides, a stationary abutment in said casing and projecting into the working space between rotor and casing and adjustable as to depth of its projection into the casing, to vary the effective size of the working chamber. 20
3. In a rotary machine, the combination of a casing, a rotary drum having radial grooves, slides arranged in said grooves, means for reciprocating said slides in an axial direction, an abutment in said casing projecting into the working space between the casing wall and the end face of the drum, means for axially adjusting said abutment, said drum being also adjustable axially together with said abutment. 30
4. In a rotary machine, the combination with a casing, a radially grooved rotor therein and a stationary abutment therein; of means to simultaneously adjust the abutment and rotor in the casing to vary the output of the machine. 35
5. In a rotary machine, the combination of a casing, a rotary drum having radial grooves, slides arranged in said grooves, means for reciprocating said slides in an axial direction, said drum being axially adjustable, an abutment in contact with the end surfaces of said drum and means for adjusting said drum and abutment. 40
6. In a rotary machine, the combination with a rotary drum therein having radial grooves, slides arranged in said grooves of a length not exceeding the length of the drum, an abutment in the casing projecting into the working space formed between the casing wall and end face of the drum, means for controlling the axial movement of the slides relatively to the drum, said drum and abutment being axially adjustable. 55
7. In a rotary machine, a casing having admission and discharge ports at each end, a radially grooved, axially adjustable rotor in the casing, slides axially slidable in the grooves, stationary abutments at each end of the casing adjustable to and from the ends of the rotor, and chambers each connecting an admission port at one end of the

casing with a discharge port at the other end.

8. In a rotary machine, a casing having admission and exhaust ports, a radially grooved rotor in the casing, slides reciprocable in the grooves, an adjustable abutment with which said slides coöperate and which varies the effective working space swept by the slides to vary the delivery of the machine, and means both external of and internal of the machine to effect communication of the admission and delivery sides thereof. 70

9. In a rotary machine, a casing having admission and exhaust ports, a radially grooved, axially adjustable rotor in the casing, slides reciprocable in the grooves, an axially adjustable abutment with which said slides coöperate and which varies the effective working space swept by the slides 80 to vary the delivery of the machine, and means both external of and internal of the machine to effect communication of the admission and delivery sides thereof. 85

10. The combination of two rotary machines, each of these machines having in combination, a rotary drum provided with radial grooves, slides arranged in said grooves, means for reciprocating said slides, one of said machines having its drum 90 axially adjustable, an abutment in the casing projecting into the space between the end wall of the casing and the side surface of the drum, and means for axially adjusting said abutment, the suction side of each 100 machine being in communication with the delivery side of the other machine.

11. The combination of two rotary machines, each of these machines having in combination, a rotary drum having radial 105 grooves, slides arranged in the grooves, means for reciprocating said slides and one of said machines having its drum axially adjustable, an abutment in its casing projecting to an adjustable depth into the space 110 between the end wall of the casing and the side surface of the drum, and means for axially adjusting said drum and abutment, the suction side of each machine being in communication with the delivery side of the 115 other machine.

12. A rotary machine representing a combination of two partial machines, these machines having a casing common to both of them, a drum common to both of them in 120 said casing, provided with radial grooves, slides arranged in said grooves, means for reciprocating said slides in an axial direction, said drum being axially adjustable, abutments in said casing projecting to an 125 adjustable depth into the spaces between the end walls of the casing and the end surfaces of the drum, means for axially adjusting said drum and abutments, the suction side of each partial machine being in commun- 130

cation with the delivery side of the other partial machine.

13. A rotary machine having a casing, a rotary drum in said casing, said drum having radial grooves, slides arranged in said grooves, means for reciprocating said slides in an axial direction, said drum being axially adjustable, abutments projecting into the spaces between the end walls of the casing and the end surfaces of the drum, means for axially adjusting said drum and abutments, said drum having an axial passage between each two adjacent slides.

14. A variable speed driving mechanism having in combination, a pump consisting of a casing, a rotary drum having radial grooves, slides arranged in said grooves, means for reciprocating said slides in an axial direction, an abutment in said casing projecting into the working space between the casing wall and the side face of the drum, means for axially adjusting said abutment, said drum being also adjustable axially together with said abutment, and a motor in working communication with said pump.

15. A variable speed driving mechanism having in combination a pump consisting of a casing, a rotary drum having radial grooves, slides arranged in said grooves, means for reciprocating said slides in an axial direction, said drum being axially adjustable, an abutment in contact with the end surface of said drum, means for adjusting said drum and abutment, and a motor in working communication with said pump.

16. In a rotary machine, the combination with a casing having admission and discharge ports, an adjustable, radially grooved rotor, slides movable in the grooves of the rotor, a spring-urged abutment coöperating with the ends of the slides and means to axially adjust the rotor, said abutment be-

ing displaced against the stress of its spring by said rotor during its adjustment.

17. In a rotary machine, the combination with a casing having admission and discharge ports, a radially grooved rotor in the casing, slides axially movable in the rotor grooves, spring-urged adjustable abutments projecting into the ends of the casing means to limit the extent of their projection into the casing, means to axially adjust the rotor and simultaneously adjust one or the other abutment against the action of its spring.

18. In a rotary machine, a casing, a sectional lining therefor, the opposed ends of said lining formed as cam surfaces, and means to hold said sections apart to form a cam groove between the opposed sections.

19. A variable speed and reversing mechanism having in combination rotary units action as pumps, said units having a common casing, a drum common to both of them in said casing and provided with radial grooves, slides arranged in said grooves, means for reciprocating said slides in an axial direction, said drum being axially adjustable, abutments in said casing, projecting to an adjustable depth into the spaces between the end walls of the casing and the end surfaces of the drum, means for axially adjusting said drum and abutments, the suction side of each unit being in communication with the delivery side of the other, and a motor in working communication with said units.

In testimony that I claim the foregoing as my invention, I have signed my name in presence of two subscribing witnesses.

JOSEPH LEHNE.
